WHEEL COVER

Howard M. Jenkins, Jr., Detroit, Mich., assignor
to Van Auken, Inc., Detroit, Mich., a corpora-
tion of Michigan

Application June 9, 1952, Serial No. 20,104

Term of patent 14 years

(Cl. D14—30)

To all whom it may concern:

Be it known that I, Howard M. Jenkins, Jr., a citizen of the United States, residing at Detroit, Wayne County, Michigan, have invented a new, original, and ornamental Design for a Wheel Cover, of which the following is a specification, reference being had to the accompanying drawing forming a part thereof, in which:

Figure 1 is a side elevational view of my novel design for a wheel cover; and

Figure 2 is a profile view showing the contour of the cover of Figure 1.

The dotted lines in Figs. 1 and 2 showing a conventional hub cap design in the central portion of the wheel cover are for illustrative purposes only.

I claim:

The ornamental design for a wheel cover, as shown and described.

HOWARD M. JENKINS, JR.
